Primary Examiner — John Windmuller*Assistant Examiner* — Benjamin M Weeks(74) *Attorney, Agent, or Firm* — Tucker Ellis LLP(57) **CLAIM**

The ornamental design for a tractor for construction vehicle, as shown and described.

DESCRIPTION

FIG. 1 is a perspective view of a tractor for construction vehicle showing my new design.

FIG. 2 is another perspective view thereof.

FIG. 3 is a front view thereof.

FIG. 4 is a rear view thereof.

FIG. 5 is a left side view thereof.

FIG. 6 is a right side view thereof; and,

FIG. 7 is a top view thereof.

The de-emphasized areas that are surrounded by broken lines shown in the drawings illustrate portions of a tractor for construction vehicle that form no part of the claimed design.
